UNITED STATES PATENT OFFICE

JOHN W. ANDERSON, OF GARY, INDIANA

WIPER

Application filed August 31, 1929. Serial No. 389,653.

My invention belongs to that general class of devices known as windshield wipers or squeegees and relates more particularly to an improved type of wiper blade or swipe, as 5 it is generally known.

The invention has among its objects the production of a simple, durable, efficient, inexpensive and satisfactory device of the kind described for use wherever found applicable.

More particularly the same has as an object, the production of a device that has all the advantages of a thin or more or less flexible and pliable wiping element, the advantages of a heavy and more or less rigid wiper element, the advantages of a single and a multiple ply wiper, with practically none of the defects of any of the types enumerated. It has as a further object the production of a device which will not only wipe clean but will be less inclined to smear and will not be rendered inoperative or inefficient through the accumulation of snow, ice, dirt or mud on, or in itself, the same being substantially self-cleaning at all times.

Many other objects and advantages of the construction herein shown and described will be obvious to those skilled in the art from the disclosure herein given.

To this end my invention consists in the novel construction, arrangement and combination of parts herein shown and described, and more particularly pointed out in the claims.

In the drawings, wherein like reference characters indicate like or corresponding parts:

Fig. 1 is a side elevation of my improved wiper applied to a windshield glass;

Fig. 2 is an enlarged sectional view taken substantially on the line 2-2 of Fig. 1;

Fig. 3 is the same view of the blade in operative relation with the surface to be wiped; and

Fig. 4 is a perspective view of a portion of the rubber strip.

Referring to the drawings in which a preferred embodiment of the invention is shown, it may be mentioned that the blade is an improvement in the type illustrated in my pending application, Serial No. 387,041, and con-

sists of a blade preferably of rubber consisting of a body part provided with a head having a plurality of arrises extending from end to end thereof. I have designated the blade generally by the numeral 1, the same consisting of a body part 2, provided with a rib or enlarged rib 3 extending along the back or rear edge thereof. The opposite edge of the body part 2 is enlarged as indicated at 4 and provided with the shoulder portions 5. At 55 this edge there is provided the head 6, which is connected to the body part or edge 4 by a hinge portion 7 of reduced size, so that the same is comparatively flexible and constitutes a hinge whereby the head portion may be 60 flexed from one side to the other for example as shown in Fig. 3. The head is comparatively thick so that in itself it does not flex or yield to any extent, other than to closely hug the surface to be wiped and is provided with 65 arrises 8, substantially similar to those shown in my pending application referred to.

The blade 1 is mounted in a holder 9 which consists of a channel or U-shaped member preferably formed with an enlarged loop at 70 the closed side with the outer ends flared as indicated at 11, so as to closely fit the body portion 2, and of a width or size so as to engage at the shoulders 5 the edge portion 4 of the body. The blade is adapted to be moved over a surface to be wiped or squeegeed as for example the outer face of a windshield glass 12, it being immaterial whether the blade is moved back and forth in a straight line or moved in an arc by means of a spring 75 arm carried by a rock shaft. For purposes of illustration, I have shown the last mentioned type of actuating means, which 16 represents the arm that swings back and forth. As shown the holder 9 is provided with an opening 14 which opening also extends 80 through the rubber blade. A clamping member 15 is secured by a bolt 17 and nut 18 and connects the holder with the arm 16. As most clearly shown in Fig. 2 the sides 19 of 85 the clamp are preferably slightly spread, the head or closed portion 10 of the holder being engaged by the sides of the clamp and secured thereto by a cotter pin 20 or equivalent 90 means.

As the device is moved back and forth over the surface to be wiped the blade is flexed back and forth at the hinge portion 7, there being also some slight play between holder and the sides 19 of the clamp. The head 6 is at all times maintained in contact with the face to be wiped and maintains uniform engagement therewith regardless of variations, in the surface or lack of careful fitting of the clamps, etc., so the wiping tends always to be uniform and even. Obviously no dirt, snow, or the like can get in between the holder and the wiping blade, and the blade is firmly held in place in the holder. Should any water, dirt, snow or ice get in the space 7' adjacent the hinge, the head working back and forth during the flexing of the hinge portion causes the same to drop out and the device thus cleans itself. It will be noted that the shoulders 20 formed at 5-5 form a stop for the head and these also at all times prevent the metal edge of the holder coming in contact with the glass or surface wiped. The device is inexpensive to manufacture and is applicable on practically any type of wiper or squeegee and has a comparatively long life in use.

Having thus described my invention, it is obvious that various immaterial modifications may be made in the same without departing from the spirit of my invention; hence, I do not wish to be understood as limiting myself to the exact form, construction, arrangement and combination of parts herein shown and described or uses mentioned.

What I claim as new and desire to secure by Letters Patent is:

1. A flexible wiping element for a squeegee, consisting of a body part provided with a rib on one edge of greater thickness than the adjacent body portion, and with a head on the opposite edge, said head and body being integrally connected together by a hinge portion of a thickness less than the thickness of the adjacent body and head,

45 whereby the head may be flexed back and forth at the hinge, the body portion constituting a stop for the head remote from said hinge portion, thereby limiting the movement of the head when flexed to either side.

50 2. A flexible wiping element for a squeegee, consisting of a body part provided with enlarged rib portion on one edge of a greater thickness than the adjacent body portion, and with a head on the opposite edge, said head

55 and body being integrally connected together by a hinge portion of a thickness less than the thickness of the adjacent body and head, whereby the head may be flexed back and forth at the hinge, the body portion constituting a stop for the head remote from said hinge portion, thereby limiting the movement of the head when flexed to either side,

60 the head tapering outwardly from the edge at the juncture with the hinge, and provided with a plurality of wiping edges.

65

3. A device of the kind described comprising a flexible wiping element for a squeegee device, consisting of a body part provided with a rib on one edge of greater thickness than the adjacent body portion, and with a head on the opposite edge, said head and body being integrally connected together by a hinge portion of a thickness less than the thickness of the adjacent body and head, whereby the head may be flexed back and forth at the hinge, the body portion constituting a stop for the head and limiting the flexing movement thereof, a U-shaped holder such as to closely fit the sides of the body and ribs, an actuating member and means for securing said holder to the actuating member to permit a limited rocking movement of the holder, supplementing the flexing movement of the wiping element.

4. A wiper for windshield cleaner blades, 85 formed of a flexible rubbery substance and comprising a body portion, a head portion, and a neck portion connecting the head portion to the body portion, the neck portion being spaced inwardly of the two sides of 90 both the head and body portions and being relatively thin in proportion to the width of both the head and the body portions and constituting a freely flexible thin web permitting the head to laterally tilt in opposite 95 directions through substantial arcs, under the light pressures normally exerted by windshield wiper arms, the head having on each side of its central longitudinal plane a plurality of longitudinal arrises.

In witness whereof, I hereunto subscribe my name this 14th day of August, A. D., 1929.

JOHN W. ANDERSON.

DISCLAIMER

1,853,715.—John W. Anderson, Gary, Ind. WIPER. Patent dated April 12, 1933
Disclaimer filed May 13, 1942, by the inventor; the assignee, Product
Inventions, Inc., assenting.

Hereby enters this disclaimer to claim 4 in said specification.

[Official Gazette June 9, 1942.]

As the device is moved back and forth over the surface to be wiped the blade is flexed back and forth at the hinge portion 7, there being also some slight play between holder and the sides 19 of the clamp. The head 6 is at all times maintained in contact with the face to be wiped and maintains uniform engagement therewith regardless of variations, in the surface or lack of careful fitting of the clamps, etc., so the wiping tends always to be uniform and even. Obviously no dirt, snow, or the like can get in between the holder and the wiping blade, and the blade is firmly held in place in the holder. Should any water, dirt, snow or ice get in the space 7' adjacent the hinge, the head working back and forth during the flexing of the hinge portion causes the same to drop out and the device thus cleans itself. It will be noted that the shoulders 20 formed at 5-5 form a stop for the head and these also at all times prevent the metal edge of the holder coming in contact with the glass or surface wiped. The device is inexpensive to manufacture and is applicable on practically any type of wiper or squeegee and has a comparatively long life in use.

Having thus described my invention, it is obvious that various immaterial modifications may be made in the same without departing from the spirit of my invention; hence, I do not wish to be understood as limiting myself to the exact form, construction, arrangement and combination of parts herein shown and described or uses mentioned.

What I claim as new and desire to secure by Letters Patent is:

1. A flexible wiping element for a squeegee, consisting of a body part provided with a rib on one edge of greater thickness than the adjacent body portion, and with a head on the opposite edge, said head and body being integrally connected together by a hinge portion of a thickness less than the thickness of the adjacent body and head,

45 whereby the head may be flexed back and forth at the hinge, the body portion constituting a stop for the head remote from said hinge portion, thereby limiting the movement of the head when flexed to either side.

50 2. A flexible wiping element for a squeegee, consisting of a body part provided with enlarged rib portion on one edge of a greater thickness than the adjacent body portion, and with a head on the opposite edge, said head

55 and body being integrally connected together by a hinge portion of a thickness less than the thickness of the adjacent body and head, whereby the head may be flexed back and forth at the hinge, the body portion constituting a stop for the head remote from said hinge portion, thereby limiting the movement of the head when flexed to either side,

60 the head tapering outwardly from the edge at the juncture with the hinge, and provided with a plurality of wiping edges.

65

3. A device of the kind described comprising a flexible wiping element for a squeegee device, consisting of a body part provided with a rib on one edge of greater thickness than the adjacent body portion, and with a head on the opposite edge, said head and body being integrally connected together by a hinge portion of a thickness less than the thickness of the adjacent body and head, whereby the head may be flexed back and forth at the hinge, the body portion constituting a stop for the head and limiting the flexing movement thereof, a U-shaped holder such as to closely fit the sides of the body and ribs, an actuating member and means for securing said holder to the actuating member to permit a limited rocking movement of the holder, supplementing the flexing movement of the wiping element.

4. A wiper for windshield cleaner blades, 85 formed of a flexible rubbery substance and comprising a body portion, a head portion, and a neck portion connecting the head portion to the body portion, the neck portion being spaced inwardly of the two sides of 90 both the head and body portions and being relatively thin in proportion to the width of both the head and the body portions and constituting a freely flexible thin web permitting the head to laterally tilt in opposite 95 directions through substantial arcs, under the light pressures normally exerted by windshield wiper arms, the head having on each side of its central longitudinal plane a plurality of longitudinal arrises.

In witness whereof, I hereunto subscribe my name this 14th day of August, A. D., 1929.
